UNITED STATES PATENT OFFICE.

JOHN NELSON AND GEORGE SEEDS, OF NEWTON, IOWA, ASSIGNEES TO AUTOMATIC ELECTRIC WASHER CO., INC., A CORPORATION OF IOWA.

OPERATING MECHANISM FOR WASHING MACHINES.

1,417,099.

Specification of Letters Patent. Patented May 23, 1922.

Application filed May 26, 1921. Serial No. 472,675.

To all whom it may concern:

Be it known that we, JOHN NELSON and GEORGE SEEDS, citizens of the United States, and residents of the city of Newton, in the 5 county of Jasper and State of Iowa, have invented certain new and useful Improvements in an Operating Mechanism for Washing Machines; and we do hereby declare that the following is a full, clear, and exact description of the same, reference being had to the accompanying drawings, and to the numerals of reference marked thereon, which form a part of this specification.

This invention relates to a driving mechanism for a washing machine of the dolly type, in which a vertical power driven shaft is operatively geared to the dolly to alternately rotate the same, and it is an object of this invention to provide a novel driving 15 mechanism that connects the vertical shaft to the dolly with provision for raising the cover of the washing machine without interfering with said driving connection.

It is a further object of this invention to 20 provide an efficient, practicable and simple mechanism having a universal or flexible joint on the line of the cover hinge.

With these and other objects in view which 25 will become more apparent in the following 30 description and disclosures in the drawing, our invention comprises the novel features of construction, combinations and arrangement of parts hereafter more specifically described and pointed out in the appended 35 claims.

In the drawing which illustrates a preferred embodiment of our invention and in which similar reference numerals refer to similar parts in the different views:

40 Figure 1 is a top plan view of a washing machine with the wringer and parts omitted showing our novel driving mechanism.

Figure 2 is a section on the line 2—2 of Figure 1.

45 Figure 3 is a section on the line 3—3 of Figure 1, showing the universal joint.

Figure 4 is a top plan view of the washing machine with the removable wringer in assembled relation and illustrating by dotted 50 lines the swinging feature of the wringer.

Figure 5 is a section on the line 5—5 of Figure 4.

On the drawings:

In referring now, to Figures 1 and 2, it 55 will be noted a vertical power driven shaft

1 is rotatably mounted on the frame of the washing machine and rises above the tub for removably supporting a wringer 2. Directly above the cover 3 of the wash tub 4, the said shaft 1 is provided with a gear 60 5 connected to said shaft by a clutch not shown. The gear 5 is enclosed in a casing or housing 6 and meshes with a gear 7 65 enclosed in a housing 8 adapted to be removably covered by a circular cover 9. The gear 7 70 is supported on a stub shaft 10 which is mounted in a socket 11 integral with a plate 12 extending across a portion of the top 75 of the wash tub. The plate 12 is provided with hinge lugs 13 to which the cover 3 is 80 hinged and an anchoring lug 14 for uniting the same to the casing 5.

The gear 7 is provided with a wrist pin 15 for receiving the hollow bearing of a pitman 16 which extends to the center line 85 of the wash tub and directly over the line of the cover hinge, where it is flexibly connected to the power arm of a gear segment 19. The flexible connection illustrated comprises a ball or spherical knob 17, on the 90 end of the pitman 16 and fitting in a socket 18 on said gear segment 19 which is pivoted at 20 to a plate member 21 having a shrouding hood 22. The plate member 21 is mounted on the cover 3 and is provided with 95 the hinge lugs 23 that are pivoted to the hinge lugs 13. Within the hood 22, the gear or rack segment 19 meshes with a gear 24 secured on the shaft of the dolly 25. The arrangement is such that when the pitman 90 16 is reciprocated, the segment gear 19 will be oscillated on its pivot 20 and operate the gear 24 which will be rotated in one direction as the pitman reciprocates forward, and in the opposite direction as the pitman reciprocates backwards. The pitman 16 may be covered by a hood 26 attached to the plate member 12 and casing 8.

The universal joint formed by the ball 17 and socket 18 directly on the line of the 100 cover 3 with the plate 12 allows the cover 3 to be raised at any time, without interfering with the driving mechanism, or stopping the same, since the operative relation of the pitman and gear segment is not impaired by 105 raising the cover; the pitman and gear segment merely flexing at the hinge line of the cover and plate 12 as is obvious.

We are aware that numerous details of construction may be varied through a wide 110

range without departing from the principles of this invention, and we therefore do not purpose limiting the patent granted otherwise than necessitated by the prior art.

5 We claim as our invention:

1. In a washing machine having a cover hinged to the top thereof, a driven shaft journalled in said cover and having a gear at its upper end, a gear segment pivoted to 10 said cover and meshing with said gear, said gear segment having a power arm provided with a socket at its end, a pitman having a spherical knob operatively connected in said socket and means for reciprocating said 15 pitman.
2. In a washing machine, a cover, a ver-

tical operating shaft extending through said cover, a gear segment pivoted on said cover, a gear on said vertical shaft meshing with said segment, and driving mechanisms for 20 said segment comprising a pitman having one of its ends pivotally engaging said segment on the hinge line of said cover.

In testimony whereof, we have hereunto subscribed our names in the presence of two 25 subscribing witnesses.

JOHN NELSON.
GEORGE SEEDS.
